UNITED STATES PATENT OFFICE.

EDWARD M. JONES, OF MACON, GEORGIA.

CREMATORIUM.

1,170,818.

Specification of Letters Patent. Patented Feb. 8, 1916.

Application filed September 28, 1914. Serial No. 863,938.

To all whom it may concern:

Be it known that I, EDWARD M. JONES, a citizen of the United States, residing at Macon, in the county of Bibb and State of Georgia, have invented a new and useful Crematory, of which the following is a specification.

The device forming the subject matter of this application is a crematory designed primarily for use in burning up night soil, garbage, etc., one of the objects of the invention being to provide novel means whereby the air is heated before it is introduced into the incinerating chamber, this heating of the air being brought about by utilizing the waste products of combustion.

Another object of the invention is to provide a crematory having an incinerating chamber and a combustion chamber extended across the incinerating chamber at one side thereof, the combustible material in the products of combustion being consumed in the combustion chamber, before such products pass through the stack.

It is within the scope of the invention to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings:—Figure 1 is a horizontal section taken approximately on the line 1—1 of Fig. 2; Fig. 2 is a vertical longitudinal section taken on the line 2—2 of Fig. 1; Fig. 3 is a cross section taken on the line 3—3 of Fig. 1; and Fig. 4 is a cross section taken on the line 4—4 of Fig. 2.

The crematory herein disclosed comprises a floor or foundation 1. Located upon or adjacent to the floor 1 are side beams 2 and 3, and rear beams 4. The lower ends of the side beams 2 and 3 are connected by tie-rods 100 which prevent a spreading of the walls of the structure, and a dropping of the arch hereinafter mentioned. The side beams 2 and 3 are connected by deck beams 5 sup-

porting a platform 6. A wall 7 is provided and projecting inwardly from the wall 7 is an incline 8. There is provided a drain 51, through which may pass rain or washing-up water. The rear portion 9 of the wall 7 is higher than the remaining portions thereof and co-operates with the rear I-beams 4 to support a platform 10. Soil is banked up as shown at 11 against the portion 9 of the wall, so that a vehicle may be driven readily onto the platforms 10 and 6. The platforms 10 and 6 are surrounded upon three sides by a parapet 12.

The structure in which the incinerating process takes place comprises a side wall 14, a side wall 15, a front wall 16 and a rear wall 17. Extended between the front wall 16 and the rear wall 17 and located relatively near to the side wall 14 is an intermediate wall 18 connected with the side wall 14 by a bridge 19, defining a combustion chamber 20. Communicating with one end of the combustion chamber 20 is a stack 21 which may be brick-lined and provided with air spaces as is common in the art. The walls of the structure may be surrounded by a metal casing 101 which prevents a leakage of air into the crematory or a leakage of gases therefrom. An arch 22 is sprung between the walls 18 and 15 and defines an incinerating chamber 23. An opening 24 in the wall 18 establishes communication between the incinerating chamber 23 and the stack 21. Openings 25 in the wall 18 establish communications between the incinerating chamber 23 and the combustion chamber 20.

In the front wall 16 there is formed a doorway 26 controlled by a door 27, the construction of which need not be described, since this door forms the subject matter of a prior patent.

Located within the incinerating chamber 23 is a cross wall 30 preferably of single thickness, the cross wall 30 extending between the front wall 16 and the rear wall 17. Extended parallel to the wall 30 is a wall 102. A wall 103 extends between the walls 102 and 30. Fitting in the rectangle defined by the walls 30—17—102—103 is a pan 29 adapted to receive night-soil, carcasses, garbage and the like. An incline 106 leads from the door 26 to the pan 29.

A grate 31 is supported by the cross wall 30 and by the side wall 15, the grate 31 ex-

tending entirely across the incinerating chamber 23 in a direction parallel to the cross wall 30, the grate 31 being suitably supported in its intermediate portion as shown at 32. Stoke doors 33 located in the walls 16 and 17 give access to the ends of the grate 31, and clean-out doors 34 are located below the stoke doors 33. The intermediate portion of the grate 31 is reached by a clean-out door 35 located below the grate as will be understood best from Fig. 4. A clean-out door 44 located in the front wall 16 gives access to the combustion chamber 20.

An arched hood 36 lies between the platform 6 and the arch 22 of the incinerating chamber, the hood 36 terminating in a horizontal extension 37 lying above the bridge 19 and above the combustion chamber 20. The hood 36 and the platform 6 define an upper draft space 38; the hood 36, the extension 37, the arch 22 of the incinerating chamber and the bridge 19 defining a lower draft space 39. The draft spaces 38 and 39 are in communication adjacent the wall 14, the upper draft space 38 being open adjacent the wall 15. Adjacent the wall 15, the lower draft space 39 communicates with the upper ends of upright flues 40, in which are located dampers 41. The lower portions of the flues 40 communicate with openings 42 discharging beneath the grate 31 near the ends thereof. Opposite to the openings 42 the flues 40 are provided with cleanout doors 104.

A night-soil conduit 43 opens through the platform 10 and discharges onto the pan 29. Access is had to the pan 29 through a door 45 located in the rear wall 17. Garbage may be deposited upon the grate 31 through the medium of a chute 46 opening through the platform 6, the chute being provided with a hinged trap door 47 carried by the platform 6. Connected with the trap door 47 is a flexible element 48 carrying a weight 49, the flexible element 48 being supported intermediate its ends as shown at 50, upon one of the I-beams which form the framework of the structure.

It is to be observed that the air enters between the hood 36 and the platform 6, and passes to the left (Fig. 2) around the extension 37 of the hood, the air passing thence between the hood 36 and extension 37 upon the one hand and the bridge 19 and the arch 22 of the combustion chamber, upon the other hand. Owing to the sinuous path in which the entering air is forced to travel, the air is heated to a considerable degree before it is passed into the incinerating chamber. It is to be observed that the air not only is heated above the incinerating chamber, but, as well, is heated above the combustion chamber 20 by the waste products passing therethrough. From the lower air space 39, the air passes by way of flues 40 and the

outlets 42, beneath the grates 31. Thence, the air is deflected upwardly by the cross wall 30 and passes across the top of the pan 29, the air passing thence downwardly through the openings 25 in the intermediate wall 18 and traversing the combustion chamber 20 to the stack 21. While the air is traversing the combustion chamber 20 waste matter carried in suspension in the smoke will be consumed prior to the entrance of the smoke into the stack 21.

Disposed upon the floor 1 beneath the platform 10 is a winch 107 controlling a flexible element 108 extended through the door 45 and adapted to be used for hauling heavy carcasses and the like up the incline 106 and onto the pan 29.

Having thus described the invention, what is claimed is:—

1. A crematory embodying an incinerating chamber; a grate disposed at one side of the incinerating chamber; an offal support disposed in approximate alinement with the grate; a platform above the incinerating chamber; a hood interposed between the top of the incinerating chamber and the platform and defining an upper draft space and a lower draft space which communicate with each other adjacent one end of the hood; means for admitting air into the upper draft space at a point remote from said end of the hood; a flue communicating with the lower draft space adjacent the other end of the hood and opening into the incinerating chamber below the grate; an upright wall constituting at once a support for the grate and a means for deflecting the air from the flue upwardly through the grate; and an outlet for the products of combustion, the outlet communicating with the incinerating chamber below the level of the offal support thereby to draw the air which passes through the grate across the offal support.

2. A crematory comprising an incinerating chamber; a transverse combustion chamber at one side of the incinerating chamber; a cross wall defining one side of the combustion chamber and one side of the incinerating chamber; a stack at one extreme end of the combustion chamber; a platform above the incinerating chamber; a hood between the top of the incinerating chamber and the platform, the platform terminating in an extension lying above the combustion chamber and extended unbrokenly entirely across the crematory from one end thereof to the flue; a grate in the incinerating chamber and extended entirely thereacross; means for admitting air to the space above the hood; and means for conducting air from the space below the hood to the space below the grate; the cross wall having a plurality of openings placed closely together, whereby the products of combustion entering the combustion chamber will heat the chamber

throughout its length and cause the chamber to heat the air passing around the extension through the entire length of the extension, one of said openings in the cross wall communicating directly with the stack thereby to prevent a deadening of the draft from the grate.

In testimony that I claim the foregoing as my own, I have hereto affixed my signature in the presence of two witnesses.

EDWARD M. JONES.
